B. MAZURYK.
 DRIVING MECHANISM.
 APPLICATION FILED OCT. 15, 1919.
1,374,214. Patented Apr. 12, 1921.

INVENTOR.

Bartłomiej Mazuryk
 BY *Alfred Schinko*

ATTORNEY.

UNITED STATES PATENT OFFICE.

BARTLOMIEJ MAZURYK, OF TUGASKE, SASKATCHEWAN, CANADA.

DRIVING MECHANISM.

1,374,214.

Specification of Letters Patent. Patented Apr. 12, 1921.

Application filed October 15, 1919. Serial No. 330,938.

To all whom it may concern:

Be it known that I, BARTLOMIEJ MAZURYK, a citizen of Ukraine, residing at Tugaske, Province of Saskatchewan, and Dominion 5 of Canada, have invented certain new and useful Improvements in Driving Mechanism, of which the following is a specification.

The object of this invention is to provide a driving mechanism especially adapted for 10 the operation of churning or the like machinery, which produces a rotative speed in excess of the speed of the driving wheel.

Another object is in the provision of 15 mechanical elements designed to reduce the labor effort usually expended in the process of churning.

These objects are attained by the novel construction and combination of parts hereinafter described and shown in the accompanying drawings, forming a material part 20 of this disclosure and in which—

Figure 1 is a top plan view of a churn, made in accordance with the invention, completely assembled.

Fig. 2 is a vertical sectional view of the same, and

Fig. 3 is a transverse sectional view taken on line 3—3 of Fig. 2.

Referring to the drawings in detail, the 30 numeral 10 indicates the base of the churn to which are attached the legs 11. Bolted to the base are hollow standards 12 and 13, and also the lower half 14 of the cream container, the same having a flange 15 around 35 its upper face, and an opening 16 in the bottom through which the butter and butter milk may be removed.

The opening 16, is normally closed by the hand-hole cover 18 located in an opening 17 40 in the base 10, and containing a packing ring 19 and secured to the container 14 by the thumb screws 20.

Attached to the standard 12, by the hinge element 21, is a casing 22 forming extensions to the standards 12 and 13 and having a central semi-circular hollow element 23 forming an upper half or cover for the lower section 14.

The elements 14 and 23 are held together 50 by the clamps 24, a packing ring 25 being interposed to prevent leakage. A conical

funnel 26 is secured to the top of the element 23 and alines with an opening in the same, providing means for the introduction of material into the churn.

A handle 30 is rotatably secured to the hand-wheel 31, which is pinned to the stub shaft 32, this shaft being journaled within the standard 13 and retained by the collars 33 and 34.

Keyed to the shaft 32 and located within the standard 13 is a spur gear 35, in mesh with the pinion 36, secured to the main shaft 40, which is journaled within the hinged casings 22 at both ends of frame. 65 Secured upon this shaft, within the casing, is spur gear 41 in mesh with the pinion 42, attached to the stub shaft 43, journaled within the standard 12 and held from lateral movement by the collars 44 and 45. Also 70 secured to the shaft 43 is the balance wheel 46.

Fixed upon the shaft 40, within the annular interior of the churn, is a series of paddles angularly positioned and forming a 75 beater wheel 48. Access to the various bearings is provided for by the removal of the covers 49 and 50.

In operation, the elements 18, 19 and 20 being secured in a proper manner, cream 80 may be poured into the churn through the funnel at the top of the machine. Rotating the hand-wheel 31 transmits its effect through the shaft and gear elements to the heavy balance wheel 46, which by the proportions of gears, derives a rotative speed in excess of the driving wheel speed, and storing energy to reduce the effort of turning the operating wheel 31.

The paddle or beater wheel being fixedly 90 retained to the rotating shaft 40 causes agitation or churning of the contents into butter in a manner which will be clearly understood.

Having thus described my invention, what 95 I claim as new and desire to secure by Letters Patent, is—

In a driving mechanism of the character described, the combination of two casings and a shaft journaled within said casings 100 at both of its ends, with pinions on said shaft within said casings, a stub shaft jour-

naled in one of said casings, a hand wheel at the outer end of said stub shaft, a pinion on said stub shaft within said casing in mesh with one of said first named pinions, a stub 5 shaft within the other casing carrying a pinion in mesh with the other of said first named pinions, an outer extension for the

first named stub shaft and a balance wheel at the outer extremity of said extension, substantially as described and for the purpose 10 set forth.

In testimony whereof I have affixed my signature.

BARTLOMIEJ MAZURYK.
